UNITED STATES PATENT OFFICE

EDWARD R. BARRETT, OF DETROIT, MICHIGAN, ASSIGNOR TO WOOD HYDRAULIC HOIST & BODY COMPANY, OF DETROIT, MICHIGAN, A CORPORATION OF MICHIGAN

THREE-WAY DUMPING BODY CONSTRUCTION

Application filed November 5, 1929. Serial No. 404,896.

This invention relates to a truck body construction particularly for the purpose of three-way dumping the contents of the body, that is, either to the rear of the truck or to either side thereof.

The bodies which are carried on trucks are subjected to very severe usage and must be exceptionally strong and durable. In the three-way dumping body, a rear tail gate is used pivotally suspended to turn upon a horizontal axis at the upper edge of the tail gate, while the sides of the body are pivotally mounted to turn about horizontal axes located at their lower edges, and the usual reinforcement which there is in a body having integral bottom, sides and front, or if not integral, permanently and rigidly secured together, is absent in bodies of the three-way dumping type. It is an object and purpose of the present invention to provide a novel construction of body particularly adapted for and capable of withstanding the very severe usage to which it is subjected in service and to make the same exceptionally strong and durable and yet not excessively heavy.

An understanding of the invention for the attainment of the ends stated, as well as many others not at this time specifically enumerated, may be had from the following description taken in connection with the accompanying drawings, in which,

Fig. 1 is a side elevation of the body, certain parts being shown in section for a better disclosure of structure.

Fig. 2 is a partial rear elevation and transverse vertical section through the body.

Fig. 3 is a fragmentary perspective view illustrating the frame construction of the body at each corner thereof.

Fig. 4 is a plan view of the under frame work of the body, the bottom and sides being removed and certain vertical posts shown in horizontal section, and

Fig. 5 is a fragmentary perspective view showing the essential elements of the bottom supporting frame work in separated relation, the view being taken of those parts of the frame work at one corner thereof.

Like reference characters refer to like

parts in the different figures of the drawings.

In the construction a lower supporting frame is provided including two spaced apart longitudinal channels having vertical webs 1 and upper and lower flanges 2 and 3. The channel members adjacent each end are narrowed in width so that the lower flange 4 at each end has an upward inclination. Substantially at the bend between the lower flange parts 3 and 4, a section of the lower flange is cut away leaving the opening 6 and a vertical slot 7 is cut in the web 1 at one side of the opening or recess 6 as shown in Fig. 5. At each end of each channel member the flanges 2 and 4 thereof are cut away so as to leave a projecting tongue 5 at each end of the web 1.

Two cross channels or sills also of channel form are used. Each comprises a vertical web 8 with upper and lower flanges 9 and 10 as shown, and each adjacent each end is narrowed in height so that the end portions of the lower flange 10 are inclined upwardly as indicated at 11. The upper flange 9 substantially adjacent the bend in the lower flange of the channel member is cut away as indicated at 12, and a vertical slot 13 is cut downwardly in the web 8.

This construction described permits an interfitting of the two longitudinal channels and the two cross channels with each other, the same joining together as indicated in Fig. 3, the web portions 1 of the longitudinal channels being received in the slots 13, while the web portions 8 of the cross channels enter the slot 7; the upper flanges 2 of the longitudinal channels fitting in the openings or recesses at 12, and the lower flanges 10 of the cross channels fitting in the openings or recesses 6; and when thus fitted together the parts may be securely welded making a strong and rigid structure.

At both the front and rear ends of the frame, cross end channels are used comprising vertical webs 14 and upper and lower flanges 15 and 16, the upper flange 15 at each end being slightly cut away as indicated at 17. These end channels may be applied against the ends of the longitudinal channel

frame members, the tongues 5 entering between the upper and lower flanges 15 and 16 and a secure welding connection of the parts provided.

5 The bottom frame is completed by two longitudinal side members of angle formation having vertical legs 18 and outwardly extending horizontal legs 19. The horizontal leg of each at each end is cut away and also 10 a small portion of the vertical leg 18 at both the upper and lower edges, providing a projecting tongue 20 which likewise is adapted to enter between the upper and lower flanges 15 and 16 of the end cross channels and be welded thereto; while the ends of the first 15 mentioned cross members abut against the sides of the legs 18 and are securely welded thereto.

20 The bottom frame thus made at each corner is provided with an L-shaped member including vertical posts 21 from which a horizontal arm 22 extends. The vertical posts pass along the outer sides of and adjacent the ends of the webs 14 of the end channels to which they are securely welded. The horizontal arms 22 extend under the lower flanges 16 and said arms at their inner ends are provided with integral brackets 23 which lie against the vertical legs 18 and are bolted 25 thereto, as best shown in Fig. 3.

30 The ends of the end cross channels extend a short distance beyond the angle longitudinal members of the frame and a member 24 fits into the projecting end portions of said end cross channels and is permanently secured thereto by welding, forming a support for a horizontal trunnion 25 extending therefrom. There are two trunnions 25 at each side of the frame structure which are in 35 axial alignment. Between the trunnions at each side as described, a metal tube 26 is disposed, the two trunnions being inserted into the ends of the tube. A plurality of vertical posts 27 are secured at the ends and intermediate the ends of the tubes 26 to which the sides 28 of the body are permanently connected. This provides a construction where- 40 in the sides may be turned about the axes of the trunnions 25 at each side of the body.

45 A bottom 29 of sheet metal is located above the various upper flanges 2, 9, 15 and 19 of the under supporting frame and is permanently attached thereto. A vertical front 39 is disposed between the front vertical posts 21. The usual pivotally suspended tail gate 31 is carried by and between the upper ends 50 of the rear vertical posts 21 and may be latched in position with the old and well-known type of latch indicated at 32.

55 The construction described provides a very strong, rigid and durable construction in the matter of three-way dumping bodies and one which, in order to secure the necessary strength, rigidity and durability which it 60 must have to withstand the service it under-

goes, it is not necessary to use exceptionally heavy and cumbersome frame members but the frame structure is relatively light in weight and at the same time amply strong, rigid and durable. The construction is one 70 readily and easily manufactured and it has proved particularly satisfactory in service. The invention is defined in the appended claims and is to be considered comprehensive of all forms of structure coming within their 75 scope.

I claim:

1. In an underframe structure having longitudinal beams and transverse beams the combination with side frame members of 80 angle iron form located one at each side of said frame and at the ends of the transverse beams, transverse channel members located at the ends of and welded to said longitudinal beams, said side frame members 85 being welded at their ends to said transverse channel members, and said channel members having end portions projecting beyond said side members of the frame, and a bracket member secured at each corner of the frame 90 comprising a vertical post and a horizontal arm extending from said vertical post at its lower end, the vertical posts having a welded connection to the adjacent end portions of the said transverse channel members, and means 95 connecting said horizontal arms to the adjacent side members of the frame.

2. In a construction of the class described, a frame, a vertical post at each corner of the frame and extending upwardly therefrom, horizontal trunnions located at each corner of the frame, two of said trunnions being located in horizontal alignment at each side of the frame, an elongated metal tube mounted at each side of the frame on said trunnions, and vertical sides of sheet metal secured to said tubes. 100

3. In a construction of the class described, a horizontal frame including end transverse beams and side longitudinal members connected together at the corners of the frame, the end transverse beams having end portions projecting outwardly beyond said side longitudinal members, a horizontal trunnion mounted on and secured to the projecting 115 end portions of each end transverse beam, the trunnions at each side of the frame lying in longitudinal alignment, vertical corner posts secured to the frame, and sides pivotally mounted on and located between the 120 trunnions at each side of the construction adapted to be turned to vertical position and located between the vertical posts at each side of the frame when in vertical position. 110

4. A construction comprising two intermediate longitudinal beams of channel form spaced from each other and two intermediate transverse beams of channel form spaced from each other, said longitudinal beams at 125 their under sides and at a distance from each 130

end thereof and said transverse beams at their upper sides and at a distance from each end thereof having parts cut away whereby the longitudinal and transverse beams may be interlocked together with their upper and lower flanges in the same planes, said beams being welded together, transverse beams of channel form located at the ends of the longitudinal beams, said ends of the longitudinal beams having portions of their flanges cut away to provide projecting tongues received in the channels of said end transverse beams and welded thereto, side longitudinal members of angle form having horizontal flanges located in the same plane with the upper flanges of said longitudinal and transverse beams, said side members having parts cut away at their ends to form projecting tongues received in the channels of the end transverse beams and welded thereto, substantially as and for the purposes described.

5. A construction containing the elements in combination defined in claim 4, combined with vertical corner posts located one at each corner of the frame and having a permanent connection to the end portions of said end transverse beams, horizontal arms extending inwardly from the lower ends of said posts and means connecting said horizontal arms to the downwardly extending flanges of the side longitudinal members of said frame.

In testimony whereof I affix my signature.

EDWARD R. BARRETT.
